(57) CLAIM

The ornamental design for a practice hockey board with attachments, as shown and described.

DESCRIPTION

FIG. 1 is a perspective view of a practice hockey board with attachments showing my new design;

FIG. 2 is an enlarged scale front elevational view of an attachment to a hockey board therefore;

FIG. 3 is a rear elevational view thereof;

FIG. 4 is a bottom plan view thereof;

FIG. 5 is a top plan view thereof;

FIG. 6 is a right side elevational view thereof; and,

FIG. 7 is a left side elevational view thereof.

The broken line showing a hockey board is for illustrative purpose only and forms no part of the claimed design.
